UNITED STATES PATENT OFFICE.

CHARLES E. ROGERS, OF BOSTON, MASSACHUSETTS, ASSIGNOR TO HIMSELF
AND ALBERT E. MANNING, OF SAME PLACE.

IMPROVEMENT IN PIANO-FORTE ACTIONS.

Specification forming part of Letters Patent No. 124,289, dated March 5, 1872.

To all persons to whom these presents may come:

Be it known that I, CHARLES E. ROGERS, of Boston, of the county of Suffolk and State of Massachusetts, have invented a new and useful Improvement in Piano-Forte Actions; and do hereby declare the same to be fully described in the following specification and represented in the accompanying drawing, which exhibits a front elevation of it.

The improved action is specially intended for upright pianos, my invention or improvement having reference to the construction and arrangement of the parts of the action.

In the drawing, A denotes the key-board; B, a key; C, the hammer; and D, a string; the latter standing vertically or in a vertical plane, or thereabout. The tail-block *a* of the hammer is represented as pivoted at *b* in a stationary projection, *c*, extended from a fixed rail, *d*, there being a short arm, *e*, projecting down from the said tail-block, in manner as shown. This arm *e* is to co-operate with an adjustable button, *f*, to effect or aid in effecting the return of the hammer after each blow of it upon the string. The said adjustable button has its screw-shank screwed through a hammer-lifter, *E*, formed and arranged beneath the tail of the hammer, in manner as shown, and connected thereto by a loop, *g*, extended from such lifter and hitched upon a hook, *h*, projecting from the tail of the hammer. The loop and hook insure the preservation of the lifter and the hammer in their due relations, and aid in retracting the hammer after each blow of it. The said lifter *E* is connected with the lower end of an elevator-arm, *F*, by means of an eyed screw, *i*, which screws up into the said arm, a screw, *k*, going through the eye of the screw *i*, and being screwed into the lifter. The elevator-arm, being analogous to a hammer-arm, is in two parts, *l m*, jointed together at *n*, and formed and provided with a counter-spring, *o*, as shown in the drawing. The upper portion *m* of the elevator-arm is fastened to and projects down from the key, in manner as shown. The back catch is represented, at *G*, as extended at an acute angle from the rear end of the key, the hammer-head being cushioned, as shown at *o'*, where it is to operate with such catch. Furthermore, there is, at the upper part of the elevator-arm *F*, a cushion, *p*, for the hammer to fall back upon. The damper is exhibited at *H*, its shank being

fastened to a block, *q*, pivoted in the arm *o*, and provided with a wire, *r*, extended downward, in manner as shown. A cushioned damper-actuator, *I*, formed as represented, and pivoted at *s*, is connected with or applied to a pedal, *K*, by means of a pitman or rod, *t*, all being arranged as in the drawing. This pedal serves to enable a person, by his foot, to throw the damper off the string, it, preparatory to each blow of the hammer, being thrown off by the key by means of a looped cord, *u*, extended from the elevator-arm *F* to a hook, *v*, projected from the block *q*, as shown. A spring, *w*, arranged as exhibited, serves to restore the damper to the string.

I make no claim to a key-hammer and damper, such being constituent parts of all or most piano-actions. My peculiar arrangement of them and their mechanical devices of connection, as well as the construction of the latter, as hereinbefore explained, cause all of the mechanism to take up very little space in a piano-case, and enable the whole to be operated with great ease and with important advantageous results.

In the said piano-action, I claim as follows:

1. The combination of the elevator-arm *F*, composed of the parts *l m o*, as set forth, with the key *B* and the lifter *E*, arranged with the hammer, as set forth.

2. Also, the arrangement and combination of the tail-block arm *e* and the adjustable button *f* with the hammer *C*, the lifter *E*, and the elevator-arm *F*, applied to the key *B*, all being arranged and in other respects substantially as specified.

3. Also, the damper *H*, the connection-cord *u*, the hammer *C*, the key *B*, the elevator-arm *F*, and the lifter *E*, arranged and constructed substantially in manner and to operate as set forth.

4. Also, the damper *H*, the connection-cord *u*, the hammer *C*, the key *B*, the elevator-arm *F*, the lifter *E*, and the damper-actuator *I*, and pedal *K*, arranged, constructed, and combined substantially in manner as explained.

5. Also, the back catch *G*, arranged, as set forth, with respect to the key *B*, and the hammer *C*, disposed and combined with the elevating-arm *F* and lifter *E*, as explained.

Witnesses: CHARLES E. ROGERS.
